UNITED STATES PATENT OFFICE

2,512,961

WATER COOLER

Samuel O. Morrison, Pine Ridge, Pa., assignor to
Sunroc Refrigeration Company, Dover, Del., a
corporation of Delaware

Application November 21, 1947, Serial No. 787,405

4 Claims. (Cl. 62—141)

1

My invention relates to water coolers or drinking fountains which are used alone or in combination with other refrigeration devices.

A purpose of my invention is to improve the utility of a water cooler front.

A further purpose is to provide a water dispenser and preferably also a sump in the front of a water cooler which are self-contained within the front.

A further purpose is to divide the upper portion of the front of a water cooler into a plurality of laterally spaced portions or panels, preferably recessing some or all of the panels, and conveniently mounting a water dispenser and sump in one such recessed panel; a drinking cup dispenser in another; and a drinking cup disposal in or accessible through another panel.

A further purpose is to provide a bottom recess in the front of a water cooler and to draw off the drainage water from the sump into a drainage water compartment which will be drained through a cock accessible through the bottom recess.

A further purpose is to permit discharge of waste cups from a cup receptor through the bottom recess.

A further purpose is to conceal the drainage cock and discharge of the cup receptor behind a grille which may conveniently provide inlet air for cooling of the refrigeration system.

A further purpose is to manufacture a water cooler or drinking fountain cabinet with sides separate from the front, to connect the front at its edges to the sides which preferably extend around and are integral with the back and to permit selective inner change of different fronts to conform with the ornamentation desired.

A further purpose is to provide a removable front for a water cooler cabinet which has laterally spaced panels at its upper portion, some at least of which are recessed, and one of which recessed panels includes a water dispenser and preferably also a sump, and to provide a bottom recess in the front in which an operator for the water dispenser is located; and preferably also access is provided to a drainage cock.

Further purposes appear in the specification and in the claims.

In the drawings I have chosen to illustrate one only of the numerous embodiments of which my invention appears, choosing the form shown from the standpoints of convenience in illustration, satisfactory operation and clear demonstration of the principles involved.

Figure 1 is a front elevation of the improved water cooler of the present invention.

2

Figure 2 is a section of Figure 1 on the line 2—2.

Figure 3 is a reduced top plan view with the lid construction broken away to illustrate the interior.

Figure 4 is a reduced front elevation with the grille broken away to show the interior construction.

Figure 5 is a right side elevation of Figure 4.

Figure 6 is a rear elevation of Figure 4.

Figure 7 is a front elevation of the cup receptor.

Figure 8 is a diagrammatic view of the refrigeration unit.

In prior art water cooler constructions the dispenser has usually been in the form of bubbler or faucet or both located at the top. This has rendered access to the interior very difficult due to the fact that the top could not be opened and interior compartments could not be entered in this manner. Auxiliary devices such as cup dispensers and cup receptors have either been mounted on the outside, or in the case of the receptors provided in the form of separate receptacles at the base of the cooler. Arrangements of this character have been undoubtedly expensive from the standpoint of cleaning services in offices and the like, have been unattractive, and constant sources of danger to the user through striking against or falling over separate accessories. In addition such prior art arrangements have been unattractive, and in some cases have necessitated shipment of coolers having protruding elements, which are vulnerable from the standpoint of damage.

In accordance with the present invention these difficulties have been overcome without greatly complicating the construction or adding to the expense. A very novel and useful water cooler front has been designed which entirely frees the top for access into internal compartments.

Certain aspects of the device herein described but not claimed form the subject matter of the copending patent application of Orville C. Morrison, Samuel O. Morrison, John G. Wehrwein and Earl Gott, Serial No. 6,924, filed February 7, 1948, for Refrigerator and Water Cooler.

The cabinet 20 is primarily of rectangular form having a top 21, bottom 22, front 23, rear 24 and sides 25. The front is bent around and joined at 23 to the sides which are preferably integral with the back.

The front is divided essentially into an upper portion 26 primarily concerned with dispensing, an intermediate portion 27 and a bottom portion 28.

The upper portion is suitably subdivided into

a left hand panel 30, a middle panel 31 and a right hand side panel 32, preferably divided by ribs 33 and 34.

While the bulk of the cabinet will conventionally be formed of metal, the upper or dispensing portion 26 of the front and desirably the entire front as shown may desirably be made of plastic from an integral piece as shown in Figure 2. The outer edges are conveniently turned around at 35 to join the rest of the wrapper of the cabinet as shown in Figure 2.

The central panel 31 and one side panel 30 are suitably deeply recessed at 36 and 37 as best seen in Figure 2.

In the central panel 31 the recess conveniently tapers inwardly from the top at 40 approximately half way down to reach the maximum depth at the point of mounting the dispenser 41 in the back of the recess. The dispenser 41 may be of any suitable type, but will preferably be a faucet operated by a foot pedal 42 in a bottom recess 43 extending deep into the lower portion 28. The foot pedal is pivoted at 44 and pivotally connected by a pull rod 45 to the operating lever 46 of a valve 47 which controls flow through the dispenser. Below the dispenser the recess 36 remains deep as shown and is carried below the outer edge 50 at the back to form a sump or catch basin 51 in the bottom.

The left hand panel 30 has in its recess 37 a cup dispenser 52 comprising a support and operating mechanism 53, a cover 54, an operating lever 55 and showing a cup at 56. The bottom of the recess 37 is conveniently sloped outwardly at 57 to aid in guiding a cup outwardly.

A cup receptor is provided in cooperation with the right hand panel 32. A recess 60 through this panel is closed by a swinging closure 61 suitably hinged at the top at 62. Behind the recess 60 and in line therewith is provided a cup receptor 63 conveniently of tubular form and suitably open at the top. The bottom is closed by a telescoping closure cup 65 which surrounds the lower end of the receptor and is held thereon removable by a spring latch 66.

A cooperating opening 67 in the cup receptor is located immediately behind the opening 60.

The discharge of the cup receptor is conveniently located behind an ornamental grille 70 in the middle portion 27 of the front, and is accessible for removal by reaching up through the open top of bottom recess 43. The fronts will be readily changed to permit various ornamentations of the grille or of the other portions of the fronts, and various colorings of acrylic phenolic or other plastics, or of enamelled or painted steel, aluminum or other metal. The cup receptor will preferably be rigidly fastened in place but may be bodily removable if desired.

Drainage from the sump 51 is provided through a drainage opening 71 and a connection 72 to a waste water compartment 73 located below the sump and conveniently behind the grille. The waste water compartment 73 is conveniently drained by a cock 74 accessible through the open top of the bottom recess 43.

As explained in connection with the copending application above referred to, the connection 72 should be sufficiently tight so that in case of overfilling the waste water compartment 73, waste water will back up and show in the sump. Also shown in said copending application, a suitable valve 75 may be located in a pipe connection 76 from a water cooling compartment 77 to the dispenser to cut off water from the dispenser under action of a float arm

80 when the water rises too high in the waste water compartment.

The water cooling compartment 77 is conveniently located in one side of the top portion 26, the other side 81 being conveniently occupied by a refrigerator for storage of food or deep freezing, suitably provided with ice cube trays 82 on cooling unit shelves 83 and 84.

The water cooling compartment and the refrigerator compartment are conveniently separated by a partition 85. An inner lid 86 hinged at 87 covers the water cooling compartment alone and an outer lid 90 hinged at 91 covers both compartments. The entire outside space of the water cooling unit and refrigeration unit are insulated at 92.

Inlet of water, either suitably poured in or from a pressure source, is provided at 93 suitably controlled by a valve 94 operated by a float arm 95 to prevent overfilling. If desired water may be poured in by simply opening the lids. As explained in the copending application, each of the compartments 77 and 81 is independently provided with sterile lamps 96 and 97 on sockets 100 and disconnected on opening the outer lid by a switch 101.

Complete drainage of the water cooling compartment may be provided by a pipe 102 into the waste water compartment and controlled by a separate valve 103 accessible through the open top of bottom recess 43.

It will be noted that the water dispenser is located rather high with respect to the bottom of the water cooling compartment so that a body of water will remain in that compartment at all times to aid in cooling.

The bottom of the refrigeration unit is drained at 104 through a trap 105 to the waste water compartment.

The refrigeration mechanism employed suitably consists of an electric motor 106 driving a compressor 107. Heated compressed refrigerant passes through a pipe 110 through a condenser 111, preferably of static type and located in a flue 112 open from top to bottom and having an air inlet 113 at the bottom and an air outlet 114 at the top. Air circulation through the flue is also aided by taking in the air through the grille in the front and passing it into the flue through an opening 24' in the back. From the condenser cooled refrigerant passes through a metering device 115 such as a constrictor or expansion valve, and thence to cooling units 116 and 117 under the respective shelves 83 and 84, and thence in series therewith to a cooling unit 120 suitably at one side in the water cooling compartment.

The refrigerant from the last cooling unit returns to the compressor through a pipe 121. The compressor is thermostatically controlled by a thermostat switch unit 122. The motor and compressor may desirably be a hermetic unit as shown at 123.

It will be evident that by the present invention I have succeeded in locating all the dispensing elements in the upper part of the front and behind the outer edge of the front so that perfectly straight lines are presented at the upper portion as seen from the side in Figure 5. The mechanism is therefore ideal not only for shipment, but also from the standpoint of cleaning and arrangement in an office or other point of use, and it presents none of the safety hazards present when cup dispensers and cup receptors were used.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters 10 Patent is:

1. In a water cooler, a cabinet of generally rectangular front having a bottom recess, an intermediate grille and an upper dispensing and disposal portion subdivided laterally into three portions, at least two of which are recessed inwardly, a water cooling compartment in the upper portion of the cabinet, water cooling means in heat transfer relation with the water cooling compartment, a mechanical refrigeration unit connected to the water cooling means, a water dispenser having water connection to the water cooling compartment and located in the recess of one of the recessed portions above the bottom thereof, a sump in the bottom of said recess, a waste water compartment below the sump and connected thereto, and a drain cock for the waste water compartment behind the grille and accessible through the bottom recess.

2. A water cooler cabinet including a top, back and side walls and a separate front secured at its edges to the side walls having at its upper portion a plurality of panels, at least some of which are recessed, a water dispenser in one of the recessed panels, walls forming a bottom recess and an operator for the water dispenser in the bottom recess.

3. In a water cooler, a cabinet having a front, a mechanical refrigeration unit including a cooling unit within the cabinet, a water cooling compartment within the cabinet, in heat transfer relation with the cooling unit, the upper por-

tion of the front of the cabinet being recessed inwardly, a water dispenser mounted in such recess and connected to the water cooling compartment, a sump located in the bottom of the recess 5 below the dispenser, a waste water compartment below the sump and connected thereto, walls forming a bottom recess in the front extending upwardly and a drain cock from the bottom compartment accessible through the bottom recess.

4. In a water cooler, a cabinet having a mechanical refrigeration unit, and a water cooling compartment cooled thereby, a removable cabinet front secured thereto and including a panel in its upper portion and walls forming a recess at the bottom thereof, a water dispenser mounted in the panel, a sump at the bottom of the panel, a waste water storage compartment below the sump connected to the sump behind the front, a 15 drain cock for the waste water storage compartment behind the front and accessible through the bottom recess and an operator for the water dispenser accessible in the bottom recess.

SAMUEL O. MORRISON.
